G. W. MULLER

RAILWAY RAIL AND TIE SECURING DEVICE

Original Filed July 9, 1925

Patented Jan. 19, 1926.

1,570,390

UNITED STATES PATENT OFFICE.

GEORGE W. MULLER, OF WASHINGTON, DISTRICT OF COLUMBIA.

RAILWAY RAIL AND TIE SECURING DEVICE.

Application filed July 9, 1925, Serial No. 42,542. Renewed October 9, 1925.

To all whom it may concern:

Be it known that I, GEORGE W. MULLER, citizen of the United States, residing at Washington, District of Columbia, have invented certain new and useful Improvements in Railway Rail and Tie Securing Devices, of which the following is a specification.

This invention relates to improvements in railway trackage, and has for one of its objects to improve and strengthen the rail supports, to enable them to withstand the increased weight of the present day locomotives and other rolling stock.

With this and other objects in view the invention consists in certain novel features of construction as hereinafter shown and described and then specifically pointed out in the claims, and in the drawings illustrative of the preferred embodiment of the invention:

Figure 1 is a side elevation of a portion of a railway track constructed in accordance with the invention.

Figure 2 is a transverse section on the line 2—2 of Figure 1.

Figure 3 is a plan view of the parts shown in Figure 1.

Figures 4 and 5 are detached perspective views from above and from beneath of one of the tie bridging plates.

Figure 6 is an enlarged sectional detail, illustrating the construction of the lower clamp device.

Figure 7 is a detached perspective view of one of the lower bridging plates.

The improved construction includes ties arranged in pairs, side by side, portions of two pairs of the ties being indicated at 10.

For the purpose of illustration, one of the load bearing rails is represented as a whole at 11, but as the construction of the rail is the subject-matter of another application it is not further described in this application.

Located beneath the ties 10 is a supporting member or rail 12 of any suitable form, for instance, of old worn out or discarded railway rails, as shown.

Bearing upon each pair of the ties 10 adjacent each of the load bearing rails 11, is a bridging plate 13, each plate having a spur 14 at the end to be driven into the tie.

One face of each spur is directed at right angles to the lower face of the plate 13, while the other face is directed at an acute angle thereto as shown in Figures 4 and 5,

so that when forced into the tie, the right angled sides of the spurs will effectually hold the plates from outward displacement, or from creeping movement away from the rails.

Each of the plates 13 is also formed with a reinforcing apertured boss 15, and a stop 16 adapted to extend between the ties 10, as shown, to constitute a spacing element thereto.

Each of the bosses 15 is also formed with a lip element 17 to extend over the adjacent portions of the tie flanges of the rails 11 and 12.

The faces of the bridging plates 13 which engage beneath the ties 10 are preferably serrated as shown at 21 in Figure 6.

A tie bolt 18 extends through the apertures of the bosses 15 and between the ties 10, and is provided with a head 19 at one end bearing against one of the bosses 15 of one of the bridging plates, and a nut 20 at the other end and bearing against the boss 15 of the other bridging plate.

Each pair of the ties 10 is spaced a distance corresponding to one of the bolts 18 and spacer members 16.

By this construction a very firm and rigid coupling is provided between the ties and rails and without the necessity for making relatively large openings or apertures in the ties; the only apertures being those made by the relatively small spurs which are negligible.

What is claimed and desired to be secured by Letters Patent is —

1. In railway trackage, ties arranged side by side, load bearing rail elements extending over the ties, supporting rail elements extending beneath the ties, bridging plates upon and beneath the ties and having lip devices projecting over the rails and spurs penetrating the ties, and clamp bolts connecting the plates and extending between the ties.

2. In railway trackage, ties arranged side by side, load bearing rails extending above the ties, supporting rail elements extending beneath the ties, bridging plates bearing above and beneath the ties and each formed with tie piercing spurs, a lug extending between the ties, and a projecting lip extending over the rail, and clamp bolts operating through the plates and between the ties.

3. In railway trackage, a pair of ties ar-

ranged as a cooperative unit to support rails, a bridging plate having rail holding means, and clamping means arranged exteriorly of and extending between the ties 5 from top to bottom thereof and operative to unite the plate and ties.

4. In railway trackage, a pair of ties arranged as a cooperative unit to support rails, a bridging plate having rail holding 10 means, and clamping means extending between the ties and including rail holding means bearing upon the under faces of the same.

5. In railway trackage, a pair of ties 15 arranged as a cooperative unit to support rails, a bridging plate adapted to be carried by said ties having rail holding means, clamping means arranged exteriorly of and extending between said ties from top to 20 bottom thereof and bearing upon the bottom faces of said ties and operative to unite the plate and ties.

6. In railway trackage, a pair of ties arranged as a cooperative unit to support 25 rails, a bridging plate having rail holding means, tie penetrating means carried by said plate, and clamping means arranged exteriorly of and extending between the ties from top to bottom thereof and operative 30 to unite the plate and ties.

7. In railway trackage, a pair of ties arranged as a cooperative unit to support rails, a bridging plate extending over the top surface of said ties with rail holding 35 means, tie penetrating means carried by said plate, a bridging plate extending over the bottom surface of said ties with rail holding means, tie penetrating means carried by said bottom plate, and clamping 40 means operative to unite said plates and ties.

8. In railway trackage, a pair of ties arranged as a cooperative unit to support rails, a bridging plate extending over the 45 top surface of said ties with rail holding means, tie penetrating means carried by said plate, a bridging plate extending over the

bottom surface of said ties with rail holding means, tie penetrating means carried by said bottom plate, and clamping means arranged exteriorly of and extending between the ties from top to bottom thereof and operative to unite said plates and ties. 50

9. In railway trackage, a pair of ties arranged as a cooperative unit, means for supporting said unit, bridging plates having means for holding said unit supporting means, rails supported by said unit, bridging plates having rail holding means, and clamping means operative to unite said 60 plates and ties.

10. A bridging plate for the purpose described formed with a boss intermediate the ends, and having rail holding lips extending laterally and vertically from the thickened 65 portion thereof.

11. A bridging plate for the purpose described formed with a boss intermediate the ends with a bolt aperture through the thickened portion thereof, and rail holding lips 70 extending laterally and vertically from the thickened portion of same.

12. A bridging plate for the purpose described, tie penetrating means depending from said plate, and rail holding lips extending laterally and vertically from said plate. 75

13. A bridging plate for the purpose described with a bolt aperture therethrough, tie penetrating means depending from said plate, and rail holding lips extending laterally and vertically from said plate. 80

14. A bridging plate for the purpose described having a bolt aperture, rail holding means, and tie penetrating means arranged substantially in alignment on the front portion thereof. 85

15. A bridging plate for the purpose described having a bolt aperture, rail holding means, and tie penetrating means arranged substantially in longitudinal alignment on the front portion thereof. 90

In testimony whereof I affix my signature.

GEORGE W. MULLER.
